BOX FOR PORTABLE TOOLS AND ACCESSORIES

Ernest F. Thomson, Tuckahoe, N. Y., assignor to Casco Products Corporation, Bridgeport, Conn.,
a corporation of Connecticut

Application December 23, 1949, Serial No. 6,809

Term of patent 7 years

(Cl. D58—11)

To all whom it may concern:

Be it known that I, Ernest F. Thomson, a citizen of the Dominion of Canada, (subject of the King of Great Britain), and residing at Tuckahoe, county of Westchester, and State of New York, have invented a new, original, and ornamental Design for a Box for Portable Tools and Accessories, of which the following is a specification, reference being had to the accompanying drawing, forming part hereof.

In the drawing:

Fig. 2 is a front elevational view thereof.

Fig. 3 is a side elevational view thereof.

I claim:

The ornamental design for a box for portable tools and accessories, substantially as shown.

ERNEST F. THOMSON.
